ARTIFICIAL DENTURE AND RETAINER
THEREFOR

John E. Brennan, Chicago, Ill.

Application January 3, 1949, Serial No. 68,949

14 Claims. (Cl. 32—2)

1

This invention relates to apparatus for retaining artificial dentures in place.

As is generally known, artificial dentures as are usually constructed comprise a gum conforming suction plate and such dentures accordingly rely upon atmospheric pressure for holding same in position.

While the dentures as are now generally constructed by the inclusion of suction plates, are generally satisfactory, particularly when same are properly fitted at the proper condition of the gums, more or less difficulty has, however, been experienced with the dentures becoming loose and failing to maintain a rigid hold on the gums.

This is particularly so as concerns the lower plate or denture for the primary reason that the lower gum is substantially less pronounced than the upper gum with the result that a lower suction plate has substantially little area contact with the gum.

The present invention, while being applicable to upper dentures, is particularly adapted for use with lower dentures, which, as above stated, do not usually hold their position as securely as do the upper dentures.

It is accordingly a primary object of the invention to provide apparatus for connection with a gum and a denture, and which apparatus includes readily releasable means whereby the denture is capable of being placed in fixed position on the gum and is also readily removable therefrom.

A further object of the invention is to provide denture securing means including an arched bar adapted to be secured to the gum by bar engaging and gum penetrating means and the denture being provided with clamps engageable with the bar and including portions accessible exteriorly of the denture for manually releasing the engagement of the clamps with the bar.

Other objects and advantages of the invention will become apparent in the course of the following detailed description, taken in connection with the accompanying drawings, wherein—

Figure 1 is a perspective view showing a lower gum with retaining apparatus, according to one embodiment of the invention, secured thereto.

Figure 2 is a side elevational view of a bar retaining ring in open position for insertion through a portion of the gum.

Figure 3 is a similar view, showing the ring closed.

Figure 4 is a front edge view of the retaining bar included in the invention, in accordance with the embodiment of Figure 1.

2

Fig. 4-A is a view similar to Figure 4 showing a modified form of bar.

Figure 4-B is also a view similar to Figure 4 and showing a still further modified form of bar.

Figure 5 is a view, more or less diagrammatic in nature and showing in particular the application of the rings to the gum, the ring being shown of exaggerated relative size.

Figure 6 is a transverse sectional view of the denture and a portion of the gum on a substantially enlarged scale, and showing in particular one of the spring clamps associated with the denture and as being operatively engaged with the bar, which is connected to the gum.

Figure 7 is a front elevational view of the denture seated on the lower gum.

Figure 8 is a view similar to Figure 1 showing the application of a second embodiment of the invention.

Figure 9 is a front edge view of the duplex retaining ring in Figure 8.

Figure 10 is a view similar to Figure 5 showing the retaining ring secured in the gum.

Figure 11 is also a view similar to Figure 1, disclosing the application of a still further embodiment of the invention.

Figure 12 is a front edge view of the retaining ring of Figure 11.

Figure 12-A is an edge view of a modified retaining ring for use with sectional dentures.

Figure 13 is a view similar to Figure 5 showing the ring of Figure 12 or Figure 12-A secured to the gum.

Figure 14 is a view similar to Figure 6 showing a single arm tooth retaining clamp which is operable only from the inner side of the tooth.

Figure 15 is a fragmental view partially in section and partially in elevation showing a modification wherein the bar is provided with multiple grooved cylindrical members in place of the knobs for engagement of the clamp sections therewith at variable distances from the bar.

The apparatus for firmly retaining the denture D in firm position on the gum G with capacity for ready removal thereof in accordance with the embodiment of Figures 1 to 7, comprises a bar 10 having clamp engageable knobs 11 rigidly supported thereby, and the apparatus further includes bar securing rings 12 and spring clamps 13 supported in the denture and preferably corresponding in number to that of the knobs on the bar.

In the application of the apparatus preparatory to removably securing a denture in position, the bar 10, which is of arcuate form, is positioned

on the ridge of the gum G as is indicated in Figure 1.

Incisions are then made in the gum at the junction of the mucous membrane and the gum tissue (Fig. 5) and the open rings 12 are then passed through such incisions, engaging as much gum tissue as possible but not penetrating the jaw bone (Figure 5). The rings are then closed around the bar which, in accordance with Figure 4, is provided with grooves 14 for receiving the rings. The rings when closed and engaged in the grooves 14 firmly retain the bar 10 in position on the gum G.

At this point it is to be noted that the bar is preferably of 14 gauge wire of gold, vitallium, nobilium or any other stainless metal, and the rings are preferably formed from the same material.

Other means may be provided for interlocking the rings with the bar; thus, according to Fig. 4-A, the bar may be provided with apertures 15 through which the rings are passed and according to Fig. 4-B the bar is provided with opposed grooves 14 and loops 16, the rings seating in the grooves and the loops acting to retain the rings in the grooves.

Other means may be resorted to for interlocking the bar and rings, the only essential consideration being that the bar 10 be rigidly anchored in position on the gum without resorting to penetration of the jaw bone.

The denture D is provided with suitable clamping means such as the clamps 13 and each clamp preferably comprises a pair of opposed relatively movable sections 17 and 18 which are pivotally connected by a pintle 19 having its ends suitably anchored in a tooth T in the denture. The tooth, together with the base or saddle B is provided with a chamber 20 which opens through the gum engaging wall of the base.

The clamp sections include arms 21 and 22 respectively which project through openings 23 and 24 in the tooth and have their free ends normally projecting beyond the inner and outer faces of the tooth as is indicated in Fig. 6. The clamp sections further include jaws 25 and 26 which grip a knob 11 under the influence of a coil spring 27 encircling the pintle 19 and having arms 28 (only one shown) engaging the arms 21 and 22.

To release the clamp, it is necessary only to press the arms 21 and 22 inwardly against the action of spring 27 whereby the denture may be readily removed from the gum.

The apparatus, according to the first embodiment of the invention, as previously described, is particularly applicable to gums which have become fully healed.

A second embodiment of the invention, particularly adapted for use where the teeth have all been extracted, is illustrated in Figs. 8, 9 and 10 and wherein the retaining bar is of dual form, including an upper bar 30' to which the knobs 31 are rigidly secured, and a lower bar 30'', the bars being preferably of a single strand in flat loop form and the bars 30' and 30'' are preferably interconnected by short vertical bars 30'.

In the application of this modified form of bar, the lower bar 30'' is imbedded in the gum G and the upper bar 30' rests on the gum as in the first embodiment of the invention. The bar 30'' is preferably positioned after making a proper incision in the gum and the bar is secured in position by means of stitches S (Fig. 10).

The third embodiment of the invention is disclosed in Figs. 11 to 13 and wherein the retain-

ing bar 32 is provided with clamp engageable knobs 33 and is also provided with substantially larger gum penetrating knobs 34.

In the application of this embodiment of the invention, the bar 32 rests on the gum G and the knobs 34 are disposed within the gum preferably through incision therein, after which the knobs 34 are secured in the gum by stitching S' (Fig. 13).

A modified form of clamp is shown in Fig. 14 as being operatively associated with a front tooth T and wherein the tooth is provided with an internal chamber 35 communicating with an opening 36 in the inside wall of the tooth. The clamp 37 includes a stationary section 38 and a movable section 39 having a pivotal connection 40, with the stationary section. The movable section 39 includes an angular arm 41 extending through and protruding from the opening 36 and a spring 42 engaged with arm 41 retains the lower ends of the clamp sections in engagement with the knobs 11.

This form of clamp is visible and operable only from the inner side of the tooth and such form may be used with a denture D as shown in Fig. 7.

The bars as disclosed in Figs. 4, 4-A and 4-B provide for application of dentures to suit different conditions. Thus, if the distance between the upper and lower jaws is relatively short, the rings 12 would be passed through openings 15 and in some instances the knobs 11 would be eliminated and the clamps engaged directly with the bar.

A modified embodiment of the invention is disclosed in Figure 15 wherein the bar 10 is provided with cylindrical members 11^a in lieu of the knobs 11 and the cylindrical members are provided with a plurality of circular grooves 11^b at different spaced distances from the bar.

This construction is particularly adaptable to suit variable spacing between upper and lower jaws since the clamp sections 17 and 18 can be engaged with any one of the grooves to suit any particular condition of jaw spacing.

From the above, it should be appreciated that the present invention provides relatively simple apparatus for firmly retaining dentures in position and that such apparatus includes readily releasable means whereby the denture may be readily removed.

While I have shown the preferred embodiment of my invention, it is to be understood that various changes in the size, shape and arrangement of parts may be resorted to without departing from the spirit of the invention and the scope of the appended claims.

Having thus described my invention in accordance with a preferred structural embodiment thereof, what I claim and desire to secure by U. S. Letters Patent is:

1. The combination with a denture, of means for retaining the denture in firm engagement with a gum, comprising an arcuate bar, means directly engageable with the gum for securing the bar thereto, and clamp means pivotally supported in the denture in a position to releasably engage said bar.

2. The structure according to claim 1, wherein said bar is provided with an integral knob releasably engageable by said clamp means.

3. The structure according to claim 1, wherein said bar is provided with a plurality of grooves, and rings adapted to extend through the gum and seat in said grooves.

4. The structure according to claim 1, wherein

said bar is provided with a plurality of apertures, and rings adapted to extend through the gum and said apertures.

5. The structure according to claim 1, wherein said bar is provided with a plurality of grooves and loops opposite the grooves, and rings adapted to extend through the gum and seat in said grooves with said loops engaging said rings to hold same in said grooves.

6. The structure according to claim 1, wherein said clamp means comprises a pair of sections disposed within a chamber in the denture and pivotally connected by a pintle anchored in a tooth included in the denture, each section having an arm projecting outwardly through an opening in the tooth, and a coil spring encircling the pintle and having opposed ends resting on the arms for normally retaining the clamp sections in engagement with the bar.

7. The combination with a denture, of means for retaining the denture in firm engagement with a gum, comprising an arcuate bar for resting on the gum, means for securing the bar directly to the gum, and clamp means for pivotal support in the denture and releasably engageable with the bar.

8. Apparatus according to claim 7, wherein said securing means comprises rings engageable with the gum and said bar.

9. Apparatus according to claim 7, wherein said securing means comprises a second bar parallel with and spaced from the first bar and being engageable within the gum.

10. Apparatus according to claim 7, wherein said securing means comprises knobs on the bar for engagement within the gum.

11. Apparatus according to claim 7 wherein said bar is provided with a knob engageable by said clamp means.

12. Apparatus according to claim 7 wherein said clamp means comprises a pair of relatively movable jaws, spring means for normally urging the jaws into clamping engagement with the bar, and one of said jaws having an arm projecting through the inner wall of said denture for release of the jaws from clamping engagement with the bar.

13. Apparatus according to claim 7, wherein said bar is provided with a cylindrical member having a plurality of circular grooves spaced axially thereof, said grooves being selectively engageable by said clamp means.

14. The combination with a denture, of means for retaining the denture in firm position on a gum, comprising an arcuate bar for support on the gum, means cooperating with the bar for engagement with the gum tissue for securing the bar in position on the gum, clamp engageable means on the bar, and a spring clamp pivotally supported within the denture for releasably engaging said clamp engageable means for removably retaining the denture in an operative position on the gum.
